INCLINED GAS NOZZLE AND HORIZONTAL
MIXING TUBE FOR GAS BURNERSHenry H. Nadasdy, Chicago, Ill., assignor to
Harper-Wyman Company, Chicago, Ill., a corporation of Illinois

Application May 9, 1947, Serial No. 747,102

10 Claims. (Cl. 158—118)

The present invention relates to and has for its primary object the provision of a new and improved gas burner assembly for inclined panel ranges and a gas valve adaptable to ranges of this type.

Another object of the present invention is to provide a new and improved structure adaptable to ordinary gas valves for projecting the gas at desired angles relative to the axis of the gas valve outlet passageway.

A further object of the present invention is to provide a gas valve of the character described above with new and improved means for projecting the gas at a desired angle relative to the axis of the valve which comprises structure enabling the angle readily to be determined in the course of manufacture.

Another object of the present invention is to provide a new and improved gas burner assembly and gas valve for inclined panel ranges so constructed and arranged as to provide the angular projection of the gas in an economical manner with the use of standardized parts and its accompanying possibility of high volume production, and permitting the use of machining lines now used for conventional valves and wherein the adaptation to inclined panels is made in the final assembly line.

Heretofore, one of the common methods for projecting the gas at different angles relative to the axis of the valve was to make the body with the desired angle cast or forged into it. This method is not satisfactory because of the large inventories required to supply the demands for the various angles desired.

Another practice is the use of a threaded adapter on the valve outlet passageway, which adapter is made to provide the desired angle. This practice is expensive due to the threading required and the necessity of having various angles on hand.

A further practice is the use of tubing and fittings connected to conventional valves and wherein the tubing is bent to the desired angle. This method is extremely expensive because of the number of parts required.

The present invention provides a simple and economical solution to the problem of supplying valves with means for projecting the gas at a desired angle relative to the axis of the valve outlet passageway. One of its advantages is that the valves are made in the usual manner up to the point of final assembly, at which point means constructed in accordance with the present invention are attached thereto. This means is a

jet which is secured to the outlet passageway and constructed with a discharge opening or orifice projecting the gas coaxially of the gas mixer tube axis. The jet may take various forms. It may be a bored element having a longitudinal milled slot, in which the angle of the milling determines the angle of projection of the gas. It may also be a solid element having a milled slot at its outer end or a solid element with a passageway having a discharge opening disposed at the desired angle. In all cases, the jet may have associated with it a movable hood to provide adjustment of the rate of gas flow—the jet preferably being fixed and the hood adjustable.

Other objects and advantages of the present invention will become apparent from the ensuing description in the course of which reference is had to the accompanying drawings, in which:

Fig. 1 is a fragmentary cross sectional view of a gas burner assembly constructed in accordance with the present invention and installed upon an inclined front panel range;

Fig. 2 is a fragmentary enlarged cross sectional view taken along line 2—2 of Fig. 3 and illustrating the construction of a single jet and its associated hood and the cooperative relationship between these and the mixer tube, although the valve illustrated in Fig. 1 includes two outlet jets because it is used with the double burner illustrated in Fig. 1;

Fig. 3 is a top plan view of the apparatus illustrated in Fig. 2, the view being taken along the line 3—3 of Fig. 2;

Fig. 4 is a view similar to Fig. 3 of another embodiment of the invention;

Fig. 5 is a cross sectional view taken along the line 5—5 of Fig. 4, showing also a portion of a mixer tube;

Fig. 6 is a transverse cross sectional view taken along the line 6—6 of Fig. 4;

Fig. 7 is a view similar to Figs. 3 and 4 of a further embodiment of the invention; and

Fig. 8 is an axial cross sectional view taken along the line 8—8 of Fig. 7, showing also a portion of the mixer tube.

In the past, almost all gas ranges have been constructed with vertically disposed front panels. In these ranges, the gas valves are secured to gas inlet manifolds with their inlets perpendicular to the gas outlets and to the valve operating stems and handles. The stems protrude perpendicularly through openings in the vertical front panel and the gas valve outlet passageways enter inlet openings in horizontal gas mixer tubes through which the gas is supplied to the burners.

The present invention is directed to a gas burner assembly and gas valve particularly adapted to gas ranges having inclined front panels and one of its advantages is that it enables the major parts of the valves to be constructed as heretofore and yet provides for the adaptation of the valves to inclined front panels in the final assembly. At the same time no considerable inventory of parts is required and the construction is simple, as is its adaptability to different angles of inclination. The valves are particularly adaptable to horizontal mixer tubes but can also be used with inclined mixer tubes. The valves can also be placed either above or below the gas supply manifold.

The burner assembly of the present invention is illustrated best in Figs. 1 and 2, especially the former. While the assembly may take various forms, it has been shown in conjunction with a double burner 10 having a main burner section 12 and a central and smaller simmer burner section 14 to which gas is supplied through the main and simmer burner section mixer tubes 16 and 18 and with which are associated a double gas valve 20 having outlet assemblies 22 projecting the gas into the mixer tubes along the axes of the tubes. While but a single assembly 22 has been illustrated, similar but differently dimensioned assemblies are provided for the two burner sections. From Fig. 1 it will be noted that the major axis of the valve 20 is inclined downwardly, it being secured in this manner to and above the gas supply manifold 24 by the valve inlet 26. The valve operating stem 28 projects through the inclined front panel 30 of the range and the valve handle 32 is secured to the projecting end of the valve stem.

The valve 20 is thus of conventional construction except for the outlet assemblies 22 of the present invention which enable the valve to be used in an assembly where the axes of the valve and mixer tube are at an angle relative to each other. The outlet assemblies are alike except for the dimensions of a slot and, therefore, only one will be described. It includes novel structure 34, hereinafter termed a jet, extending generally coaxially forward of the valve outlet passageway 36 formed in the externally threaded outlet passageway defining structure 38. The jet may take various forms, as will appear hereinafter, but in Figs. 2 and 3 it may be seen to comprise a circular piece of metal having a central internal bore 40 at one end communicating with the valve outlet passageway 36. The jet is secured to the valve, preferably fixedly, as by a press fit, and it is provided with an externally knurled portion 41 for the purpose of better securing it to the valve.

The jet is provided with a discharge opening or orifice 42 at an angle relative to the axis of the jet and consisting, in this instance, of a radial slot extending over a desired length of the jet. The jet is encircled by structure 44 hereinafter termed a hood which is movably mounted by its internally threaded portion 46 upon portion 38 of the valve. Adjustment of the rate of flow of gas is effected by relative movement between the jet and hood whereby the effective size of the slot 42 is varied. As already indicated, the hood is movably mounted and can be moved axially by rotation. To enable it easily to be rotated, it is provided with a nut-like portion 48.

The angle at which the gas is projected is determined by the terminal angle of the slot, i. e., the angle of inclination of the end 50 of the slot.

Generally speaking, the end 50 is disposed to be approximately parallel to the major axis of the mixer tube and so that the gas is discharged substantially centrally along the major axis of the tube. Thus, where the mixing tube is horizontal the end 50 of the slot is horizontal, as shown in Fig. 2.

It has also been found that better operating characteristics and over a wide range of adjustment can be had if the axial surface 52 of the hood, which encircles the jet, is made fairly long, somewhat as illustrated in Fig. 2.

The jet 34, it may be noted from the foregoing, may be constructed readily and economically and can be attached to the valve in the final assembly of the latter. The valve, up to this point, can be made in the same manner as conventional valves with the result that existing machinery and methods can be used. Likewise, the hoods and jets for the different valves are the same except for the dimensions of the slot and the particular angle of inclination of the end of the slot to fit it for a particular front panel or mixer tube inclination. In double valves, i. e., valves for double burners, the two jets are identical except for slot dimensions.

A somewhat different construction is illustrated in Figs. 4 and 5 to which reference is now had. In this embodiment, the jet 55 is provided with a substantially solid circular outer end portion 56 having a radial slot 58 milled therein with its end 60 at the desired angle. The jet is held in place by what may be termed a diametrical fin-like portion 62 extending into valve outlet passageway 36 and secured as by a press fit in the latter. In this embodiment, the discharge opening is defined by the slot 58 and the surrounding hood 44, the latter being adjustable to vary the effective size of the discharge orifice and thus the rate of gas flow. In this embodiment, the gas flow is from the outlet passageway 36 through the interior 63 of the hood and the discharge opening. Here, also, the angle at which the gas is projected is determined by the angle of the end 60 of the slot relative to the axis of the valve outlet passageway.

A further embodiment of the invention is illustrated in Figs. 7 and 8 to which reference will now be had. In this embodiment the jet 64 has a substantially solid outer end portion 66 and a diametrical inner portion 67 extending into the valve outlet passageway 36 and to which it is secured as by a press fit. The end 66 of the jet has a discharge opening 68 located at the desired angle of discharge of the gas and at right angles to the outer end surface 70 of the jet so that the gas is not only projected at the desired angle but also in a uniform manner. Gas is supplied to the discharge opening 68 from the interior 63 of the hood 44 through a passageway 72 leading to the exterior surface of the end 66 of the jet.

In this embodiment of the invention the adjustment of the rate of flow of the gas is effected by varying the effective size of the hood end of the passageway 72 and this is done as before by adjustment of the hood 44.

It is believed that the operation and adjustment of the various embodiments of the invention will be apparent from the foregoing detailed descriptions thereof. It will also be noted that the present invention provides a novel gas burner assembly as well as a gas valve adapted for use on inclined panel and inclined mixer tube gas ranges. The present invention accomplishes the desired angular discharge of gas by a very eco-

nomical device which lends itself to standardization of parts and high volume production and enables the valve to be made with the use of existing machining lines and manufacturing methods up to the final assembly line. It also eliminates the necessity for a high inventory of special valves and valve parts which would otherwise be necessary. Furthermore, it is evident that the valve can be placed either above the gas supply manifold or below it.

While the present invention has been described in detail in connection with different embodiments of the invention, it should be understood that the details thereof are not intended to be limitative of the invention except in so far as set forth in the accompanying claims.

What I claim as new and desire to secure by Letters Patent of the United States is:

1. A gas burner assembly including a mixer tube, a gas valve having valve body structure defining an outlet passageway terminating at an angle relative to the axis of the mixer tube, and discharge defining structure extending from said outlet passageway and including a jet means extending from said structure, said structure and jet means extending only coaxially of said passageway and having a discharge opening having its axis located substantially coaxially of the axis of said mixer tube for projecting gas into said tube.

2. A gas burner assembly as set forth in claim 1 wherein said jet means extending from said structure terminates in a surface inclined relative to the axis of said outlet passageway and the axis of said discharge opening located substantially coaxially of the axis of said mixer tube is substantially normal to said inclined surface.

3. A gas burner assembly as set forth in claim 1 wherein said jet means extending from said structure has a generally diametrical inner end secured to said structure and a substantially cylindrical outer end, the latter having formed therein said discharge opening.

4. A gas burner assembly as set forth in claim 1 wherein said jet means extending from said structure has an inner diametrical end secured to said structure and an outer cylindrical end having an inclined outer surface, said discharge opening being formed in said cylindrical end and having its inlet end open to the periphery of said outer cylindrical end and its exit end substantially normal to said inclined outer surface.

5. A gas burner assembly as set forth in claim 1 wherein said jet means extending from said structure has a generally diametrical inner end secured to said structure and a substantially cylindrical outer end, said cylindrical outer end having formed therein a slot forming said discharge opening having its axis located substantially coaxially of the axis of said mixer tube.

6. A gas burner assembly including a mixer tube, a gas valve having valve body structure defining an outlet passageway terminating at an angle relative to the axis of the mixer tube, discharge defining structure extending from said passageway generally coaxially of said passageway and having a discharge opening located substantially coaxially of the axis of said mixer tube

for projecting gas into said tube, and means including a hood located coaxially of said outlet passageway and movably mounted on said outlet passageway defining structure and operatively associated with said opening for adjusting the rate of flow of gas through said opening.

7. A gas burner assembly as set forth in claim 6 wherein said discharge defining structure extending from said passageway includes jet means extending from said structure having an inner diametrical end secured to said structure and an outer cylindrical end with an inclined outer surface, said discharge opening being formed in said cylindrical end and having its inlet end open to the periphery of said outer cylindrical end and its exit end substantially normal to said inclined outer surface, said means including said hood being operatively associated with said inlet portion open to the periphery of said cylindrical end.

8. A gas valve including valve body structure defining an outlet passageway, a jet member having a peripheral slot extending axially thereof secured to and extending from said outlet passageway and defining structure extending generally coaxially of said passageway, said jet having a discharge opening located at an angle relative to the axis of said outlet passageway and communicating with said peripherally slotted portion of said jet, and a hood mounted on said body structure and encircling said jet, said hood and jet being relatively movable to vary the extent of said discharge opening and thereby adjust the rate of flow of gas through the same.

9. A gas valve as set forth in claim 8 wherein said jet member having a peripheral slot extending axially therethrough is tubular.

10. A jet member for use in a gas burner assembly, said jet member comprising a substantially cylindrically shaped body having a closed end and a bore extending through part of the length of said body, means forming a peripheral slot extending substantially axially of said cylindrical body and communicating with said bore, and a discharge opening located beyond the end of said bore at an angle to the longitudinal axis of said bore and communicating with said peripherally slotted portion of said jet.

HENRY H. NADASDY.
